FEED MECHANISM AND CONTROL FOR
CONTINUOUS STOCK MATERIAL

George Albert Lyon, Detroit, Mich.

Application October 26, 1949, Serial No. 123,730

5 Claims. (Cl. 113—38)

1

This invention relates to improvements in a feed mechanism and control for continuous stock material particularly adapted to intermittently feed sheet material to a work performing apparatus, such as a hydraulic press, in accurately measured lengths.

My invention has, among other objects, to provide a new and simplified form of control means arranged to automatically control the intermittent feeding of sheet material to a working station in coordination with the work performed thereon.

Another object of my invention is to provide a novel and efficient form of control for feeding sheet material to a work performing apparatus, actuated by operation of the apparatus during its various work performing operations, and so constructed and arranged as to automatically and accurately feed predetermined lengths of sheet material in a more positive and facile manner than formerly.

Still another object of my invention is to provide a reciprocably movable table with gripping means thereon to positively grip the sheet stock, with a novel form of operating and control means therefor operable to effect positive gripping of the sheet stock and translational movement thereof to a working station, operable by the position of the table and operating parts of the working station with respect to the stock to be worked upon.

Still another object of my invention is to provide a coordinated control for feeding stock to a press, so arranged as to effect translation movement of the stock toward the press upon predetermined positions of the working head thereof.

Still another and more detailed object of my invention is to provide a novel and improved form of feed adapted to feed sheet stock to a press of the type having a vertically movable cushion coming into engagement with the material during the working stroke of the press, and including means for gripping the stock and translationally moving it toward the press into position to be worked upon, together with fluid valves controlling the various gripping and feeding operations, and actuating and control means therefor operated by the various moving parts of the press and feeding device.

In carrying out my invention I provide a translationally movable table to support the sheet material to be worked upon and provide clamping devices on the table together with means for positively moving the clamping devices into and out of engagement with the material to be worked

2

upon. I also provide means for moving the table toward and from the press and provide solenoids to control operation of the gripping and feeding means together with a novel form and arrangement of switches on the press and the feeding mechanism, controlled by movement of the press toward and from the work and connected to operate the solenoids at predetermined time intervals dependent upon the position of the cushion of the press with respect to the stock to be worked upon.

This invention is a continuation-in-part of an application Serial Number 100,365, filed by me on June 21, 1949, and entitled "Continuous Web Feeding Mechanism."

15 These and other objects of my invention will appear from time to time as the following specification proceeds and the reference to the accompanying drawings wherein:

Figure 1 is a view in side elevation of a stock feeding mechanism constructed in accordance with my invention;

Figure 2 is a top plan view of the device shown in Figure 1; showing the sheet supported thereon, with a part thereof broken away in order to more clearly illustrate certain details of the feeding mechanism therefor;

Figure 3 is a view in side elevation of the feeding mechanism shown in Figure 1, drawn to a reduced scale and showing the feeding mechanism at the receiving end of a press adapted to work upon material supplied thereto;

Figure 4 is an enlarged fragmentary transverse sectional view taken through the mechanism for clamping the stock to the table of the feeding mechanism, and showing the clamping mechanism in a released position;

Figure 5 is a fragmentary perspective view of a piece of material showing how the material is crimped by the clamping mechanism during the feeding operation;

Figure 6 is a fragmentary front end view of a hydraulic press diagrammatically showing the switches for controlling operation of the feeding mechanism; and

Figure 7 is a diagrammatic view showing the wiring diagram of the switches operated by the press and feeding mechanism and the solenoids controlling operation of the feeding mechanism.

In the drawings 10 generally designates a feeding mechanism adapted to feed sheet stock 11 to a working table or anvil 12 of a hydraulic press 13 which may be of a well known form, adapted to sever the stock and shape it to a desired form. The feeding mechanism 10 is clearly shown and described in my application Serial Number 100,365

of which this application is a continuation-in-part, so need only herein be shown and described insofar as is necessary to make my present invention readily understandable.

The feeding mechanism 10 includes a frame structure 14 having a vertical longitudinally extending guide structure 15 extending along the top thereof for a portion of the length thereof, and forming a support and guide for a translationally movable stock feeding table 16, spaced thereabove and mounted thereon for slidable movement therealong. The table 16 has a central vertically extending web 18 depending therefrom and supported and slidably guided in the guide structure 15, as shown in my application, Serial Number 100,365.

The table 16 is translationally moved along the guide structure 15 by means of a longitudinally extending double acting cylinder 19, mounted on the top of the frame structure 14 in longitudinally spaced brackets 20, 20 projecting upwardly from the top surface of said frame structure. A piston rod 21, extensible from the cylinder 19 is pivotally connected at its forward end to an ear 22 extending laterally from the web 18, to move said plate and the table 16 along the guide structure 15, upon extensible or retractable movement of said piston rod with respect to the cylinder 19.

Fluid under pressure such as air is admitted to the head end of the cylinder 19 to extensibly move the table 16 toward the press 13 by means of a valve 25 and a conduit 26 connected to the head end of the cylinder 19. The valve 25 may be any well known form of fluid or air valve, operable by depressing either one of two plungers 31, 31 to admit air to or release it from the conduit 26 and cylinder 19, and is no part of my present invention, so need not be shown or described in detail herein.

A solenoid 27 having an armature 28 is provided to operate the valve 25. Said armature is pivotally connected at its upper end to one end of a lever arm 29 through a link 30. The lever arm 29 is pivotally connected adjacent its opposite end between a bifurcated fulcrum support 32, and has engagement with the plungers 31, 31 on opposite sides of said fulcrum support to depress either of said plungers depending upon direction of movement of said arm. A compression spring 33 engaging the underside of the lever arm 29 and encircling a vertical rod 34, extending through said lever arm adjacent its center, is provided to extend the armature 28 and open the valve 25, for release of fluid from the head end of the cylinder 19. A nut and washer indicated by reference character 35 is provided to hold said lever arm to said rod and to preload the spring 33.

Fluid under pressure is admitted to and released from the piston rod end of the cylinder 19, to translationally move the table 16 away from the press 13 through a fluid valve 37. The valve 37 is like the valve 25 and is opened by a solenoid 39, to admit fluid to the piston rod end of the cylinder 19. A pressure line or conduit 41 connects said valve to the piston rod end of the cylinder 19.

The table 16 has a clamping lever 43 pivotally mounted on each side thereof in laterally spaced relation with respect thereto. The clamping levers 43 each have an inwardly extending crimping end portion 44 movable to crimp and engage the edges of the sheet stock into V-shaped notches 45, 45 formed in the edges of support plate 46 (see Figure 4). This forms indentations 47 in opposite edges of the stock as shown in Figure 5 and

assures positive feed of the stock to the press 13 upon translational movement of the table 16. The clamping levers 43, 43 on each side of the table 16 are of a similar construction and are supported and operated in a similar manner, so one only need herein be shown and described in detail. Each lever 43 is herein shown as being pivoted intermediate its ends, but adjacent the crimping end 44 thereof, between two spaced ears 48, 48 formed integrally with the support plate 46. The plate 46 is adjustably mounted in a slot 49 formed in the table 16, and is suitably secured thereto and affords a means for adjusting the position of the crimping end 44 of the clamping lever 43, to the various widths of stock desired. The outer end of the lever 43 is pivotally connected between a bifurcated end portion of a connecting member 50, threaded on the upper end of a rod 51. The rod 51 is slidably guided in a support plate 53 extending laterally from the support plate 46 and table 16. A spring 54, encircling said rod, is interposed between the bottom of the support plate 53 and a washer 55, held to said rod by lock nut 56, 56, to yieldably hold the crimping end 44 of lever 43 out of engagement with the edge of the stock.

A cylinder 59 is mounted on the bottom of the plate 53 and depends therefrom and has a piston rod 60 extensible from the upper end thereof, to pivot the clamping lever 43 and hold the crimping end 44 thereof in engagement with the edge of the material. The piston rod 60, as herein shown, has an enlarged end 61 having an evenly rounded upper face forming an abutment surface engageable with the underside of the lever 43, intermediate its ends, to pivot said lever against the spring 54, and move the crimping end 44 thereof into crimping engagement with the sheet material.

The fluid pressure cylinder 59 is herein shown as being a double acting cylinder, and the admission and release of fluid under pressure to and from both ends of said cylinder is controlled by a fluid valve 63, operated by a solenoid 64 through a lever arm 65 pivoted thereto, in the same manner the valves 25 and 37 are operated by their associated solenoids. The valve 63 is connected to the head ends of the cylinders 59, 59 by means of a conduit 66 connected to a transversely extending pipe 67 and conduits 69, 69, to supply fluid under pressure thereto and move the clamping levers 43, 43 into clamping engagement with the stock on the table 16. Said valve is connected to the piston rod ends of said cylinders through a conduit 70, a transversely extending pipe 71 and conduits 72, 72, connected from opposite ends of said pipe to the piston rod ends of said cylinders.

The sheet material is supported as it passes to the feeding table 16 on a transversely extending roller 73 at the entering end of the machine and journalled at its ends in bearing boxes 74, 74 mounted on the upper ends of upright support plates 75, 75 extending upwardly from opposite sides of said frame structure. Guide rollers 76, 76 are mounted in advance, but adjacent the roller 73 on vertical spindles 77, 77, extending upwardly from the plates 75, 75, to engage opposite sides of the material and align it with the table, during the feeding operation. Gibbed guides 78, 78 extend along opposite sides of the table 16 and the gibs thereof extend over the edges of the stock, to guide the stock along said table, and also to form a guide for the stock as the table is retracted to a starting position, to

again feed the sheet material into the press 13.

When the table 16 is in a retracted position, the crimping ends 44, 44 of the clamping levers 43, 43 may first be brought into engagement with the edges of the sheet stock and positively hold it in engagement with the table 16. Fluid under pressure may then be admitted to the head end of the cylinder 19 to extend the piston rod 21 therefrom and advance the table 16 along the guide structure 15, carrying the sheet stock with it and feeding it to the press 13. Feeding movement of the table 16 may be so correlated with movement of a working head 79 of the press 13, that the piston rod 21 will be at the end of its stroke and the table 16 will be in an extreme advanced position just as a cushion 80 on the bottom of said working head moves downwardly into engagement with the top surface of the sheet material, holding it into engagement with the anvil of the press. At this time, fluid under pressure may be released from the head ends of the cylinders 59, 59 and admitted to the piston rod ends thereof, to quickly retract the piston rods 60, 60 and allow the springs 54, 54 to move said clamping levers into disengaged positions. Fluid under pressure may then be admitted to the piston rod ends of the cylinders 19, 19 and released from the head ends of said cylinders, to retractably move the feeding table 16 into position to again grip opposite sides of the sheet stock material for advancing to the press 13. It is obvious that the length of translational movement of the feeding table 16 may be varied by changing the effective stroke of the piston rod 22, as by varying the volume of fluid admitted to and released from opposite ends of said cylinder.

The press may be of any well known form, preferably of the hydraulic type and, as shown in Figures 3 and 6, has a working head 79 suitably guided between two vertical columns 83, 83. Said working head has the cushion 80, mounted thereon, to first come into engagement with and to hold the material being worked upon and has a ram (not shown) vertically movable with respect to said cushion, which performs the working operations.

As herein shown two vertically spaced cams 84 and 85 are mounted on the working head 79 adjacent one column 83. The cam 84 is shown in Figure 6 as extending vertically along the working head 79 in parallel relation with respect to the column 83 and as having sloping upper and lower end portions. The cam 84 is adapted to engage inwardly extending operating levers 86 and 87 of limit switches 88 and 89 respectively. Said limit switches are mounted on the right hand column 83 in vertically spaced relation with respect to each other.

The limit switches 88 and 89 may be of any well known form and are no part of my present invention so need not herein be shown or described in detail. The limit switch 88, as shown in Figure 7, has two contacts 90 and 91, the contact 90 being closed when the lever 86 is engaged by the cam 84 at the completion of the down stroke of the working head 79, and the contact 91 being closed when the cam 84 moves out of engagement with the lever 86. The limit switch 89 is also so arranged that a contact 93 thereof is closed when its operating lever 87 is engaged by the cam 84 upon the return stroke of the working head 79, and remains opened when said cam engages said lever upon the down stroke of said working head.

A limit switch 95 having an operating lever 96 extending therefrom and adapted to be engaged by the cam 85 at the end of the up stroke of the press is likewise mounted on the right hand column 83 above the limit switches 88 and 89, and has a contact 97 which normally remains open and is closed upon engagement of the cam 85 with the operating lever 96 thereof on the extreme upper ends of the strokes of the working head 79, to control the energization of the working or return cycle of the press. The limit switch 95 is shown in Figure 7 as being connected in series with a limit switch 99 mounted on the frame structure 14 of the feeding mechanism 10 at the discharge end thereof. The limit switch 99 has an operating lever 100 adapted to be engaged by a trip bar 101 mounted on and projecting in advance of the web 18 of the table 16. This switch also controls energization of the working cycle of the press 13. Said last mentioned switches 95 and 99 are normally open and only close at the end of the return stroke of said press and feeding mechanism, to energize the working cycle of the press, and to prevent energization thereof until the feeding table 16 is at the extreme end of its feeding stroke.

A limit switch 103 is mounted on the guide structure 15 adjacent the entering end thereof and is adapted to be closed at the extreme end of return travel of the feeding table 16 and controls energization of the solenoids 64, 64 and gripping of the material with clamping levers 43, 43. The limit switch 103 is like the limit switches previously mentioned and has an operating lever 104 projecting upwardly therefrom, adapted to be engaged by the end of a trip bar 105, extending rearwardly from the web 18, to close a contact 106 of said switch and close a circuit to a coil 107 of a relay 109, and energize said coil, and close contacts 110, 111 and 112 of said relay, to complete the circuit through a coil 113 of the solenoid 64, and cause the clamping levers 43, 43 to come into clamping engagement with the sheet material on the table 16.

In Figure 7, a positive conductor 114 and a negative conductor 115 are shown. A starting switch 116 is shown as being connected in said positive and negative conductors in series with contact 119 of a relay 121 and a coil 122 of said relay. The switch 116 is herein shown as being a push button type of switch, the contacts of which open upon energization of the circuit and removal of the hand therefrom. The contact 119 is closed when the coil 122 is deenergized and opens when said coil is energized. Closing starting switch 116 will thus energize the coil 122 and open the contact 119. It will close contact 123 of said relay in conductor 124 connecting said coil with the conductor 114 through a stop switch 125. It will also close contact 126 in series with the limit switch 89 and contact 127 in series with the limit switches 95 and 99. The push button switch 125 connects the conductor 124, contact 123 and coil 122 of relay 121 to the positive line 114 and is normally closed. Said switch 125 serves to deenergize the control system and stop operation of the feeding mechanism when opened, by breaking the circuit to the coil 122 of the contactor 121, and closes as soon as the hand is removed therefrom.

A conductor 131 connects the positive line 114 with the coil 107 of the relay 109 through the starting switch 116, to energize said coil and close the contacts of said relay, upon closing of said

switch 116. A conductor 132 connects the return side of the coil 107 to the contact 91 of the limit switch 88. Said coil 107 is connected to the negative line through said switch 88 and a conductor 134. The limit switch 103 is connected from the positive line 114 to the conductor 131, and serves to energize the coil 107 of the relay 109, at the end of return travel of the table 16 when the starting switch 116 is open. Energizing coil 107 of relay 109 will close the contacts 110, 111 and 112 of said relay and energize the coil 113 of the solenoid 64 to bring the crimping ends of the clamping levers 43, 43 into clamping engagement with the sheet material. As the trip bar 105 moves away from the lever 106, the switch 103 will open. The contact 110, however, will complete the circuit to the coil 107, and will lock said relay in a closed position, until cushion 80 moves into engagement with the stock, and the cam 84 breaks the circuit through the contact 91. At this time the circuit to said coil 107 will be broken and the clamping levers 43, 43 will move to disengaged positions. The contact 90 will then be closed, to complete a circuit to a coil 139 of the solenoid 39, to energize said solenoid and actuate the back stroke of the table 16.

The contact 93 of the limit switch 89 is closed upon engagement of the cam 84 with the lever 87 during the return path of travel of the press. This closes a circuit to a coil 140 of the solenoid 27, through the contact 126 of the relay 121. This will effect opening of the valve 25 and translational movement of the table 16 toward the press 13, as the working head 79 thereof moves upwardly along the columns 83, 83.

In starting operation of the press and feeding device, the switch 116 may be closed by hand, energizing the coil 122 of the relay 121. This will close the contacts 123, 126 and 127 of said relay and will open contact 119 thereof. The switch 116 will then open when the hand is removed therefrom, the switch 125 being closed. Assuming that the working head of the press is in its extreme uppermost position when starting the press, as shown in Figure 6, and the feeding table 16 is in the extreme extended position shown in Figures 1 and 3, the cam 85 will close the limit switch 95. The trip bar 101 will also close the limit switch 99. This will energize the working cycle of the press, through suitable control devices, not herein shown or described since they are no part of my present invention.

Upon downward movement of the press the cam 84 will first engage the lever 87 of the limit switch 89, but due to the construction of said switch as previously explained, said switch will remain open. As the cushion 80 engages the stock 11, the cam 84 will come into engagement with the lever 86 of the limit switch 88. This will open the contact 91 of said switch and de-energize the coil 107 of the relay 109, opening the contacts 110, 111 and 112 thereof. Opening of contact 110 of the relay 109 will deenergize the coil 113 of the solenoid 64, allowing the springs 54, 54 to disengage the crimping ends 44, 44 of the clamping levers 43, 43 from the stock. The contact 90 will then close. This will energize the coil 139 of the solenoid 39 and open the valve 37 to supply fluid under pressure to the piston rod end of the cylinder 19, and retract the feeding table 16 along the guide structure 15. The cam 84 is of sufficient length to hold the contact 90 of the switch 88 closed

until the table 16 moves to an extreme retracted position and the trip bar 105 comes into engagement with the arm 106 of the limit switch 103, closing the contact 106 of said switch. At this point the cam 84 will be moved out of engagement with the lever 86 and the contact 90 of the limit switch 88 will open, while the contact 91 thereof will close. Closing of the contact 106 of the switch 103 will energize the coil 107 and close the contacts 110, 111 and 112 thereof. This will energize the coil 113 of the solenoid 64 and effect engagement of the clamping levers 43, 43 with the stock. As the cam 84 moves upwardly a further distance it will come into engagement with the lever 87 of the limit switch 89, closing contact 93 of said switch and completing the circuit through the coil 140 of the solenoid 27 through the contact 126 of the relay 122, energizing said solenoid and effecting opening of the valve 25, to supply fluid under pressure to the head end of the cylinder 19 and translationally move the feeding table 16 and the stock 11 clamped thereon toward the press 13. At the end of feeding movement of the table 16 the end of the trip bar 101 will engage the lever 100 of the limit switch 99 and close said switch and initiate another working cycle of the press, assuming the cam 85 has closed the switch 95.

It will be understood that modifications and variations may be effected without departing from the scope of the novel concepts of the present invention.

I claim as my invention:

1. In a feeding mechanism and in combination with a press having a vertically movable cushion and head, supporting structure means carried by said supporting structure for feeding stock to the press comprising a table and gripping means thereon for gripping the stock, means for moving the gripping means and table toward and from the press, two fluid valves controlling movement of the gripping means and table toward and from the press, a third fluid valve controlling engagement of said gripping means with the stock, a separate solenoid operatively connected with each of said valves, to operate the same, and control means for said solenoids and valves energizing said solenoids in a predetermined sequence by operation of said press and feeding mechanism comprising two spaced switches on the press, each being connected with one of said solenoids to effect the sequential energization thereof, and the operation of said two fluid valves, a third switch on said supporting structure and connected with the solenoid for operating said third fluid valve, a cam movable with the cushion and head of the press to engage said first two switches in a predetermined sequence and energize the associated solenoids at predetermined points in the cycle of operation of said press, another switch on said press closed upon extreme retractable movement of the cushion and head and controlling energization of the working cycle of said press, a switch operating member on said table for operating said third switch and energizing the solenoid associated therewith at the end of the return stroke of said table to effect gripping of the stock, and a further switch on said supporting structure closed by a switch actuator on said table upon movement of said gripping means to an extreme advance position, said further switch having its contacts connected in series with the contacts of said last mentioned switch on the press for

energizing the working cycle of the press upon movement of the gripping means to the extreme end of the feeding stroke thereof.

2. In a feeding mechanism and in combination with a press having a vertically movable cushion and head, supporting structure, means carried by the supporting structure for feeding stock to the press comprising a table movable toward and from the press and gripping means on said table for gripping the stock, other means for translationally moving the table and gripping means toward and from the press, two fluid valves, one controlling translational movement of the table and gripping means toward the press and the other controlling translational movement of the table and gripping means from the press, a third fluid valve controlling engagement of said gripping means with the stock, a separate solenoid operatively connected with each of said valves, to operate the same, and sequentially operated control means for said solenoids and valves comprising two spaced switches on the press, each connected with one of said solenoids to sequentially energize said solenoids, a switch on the supporting structure connected with the solenoid for operating said third fluid valve, to energize said solenoid, a cam movable with the cushion and head of the press to sequentially close said switches on the press, a switch actuator movable with said gripping means to effect closing of said switch on the supporting structure, upon movement of said table and gripping means to a retracted position, to energize said solenoid for operating said third valve and effect engagement of said gripping means with the stock, a relay having a coil connected in series with the contacts of said switch on the supporting structure and energized upon the closing of such switch, the switch on said press energizing the solenoid operating the valve controlling retractable movement of said feeding means, having contacts in series with the coil of said relay to energize the same upon the closing of said switch on the supporting structure, and also having a second set of contacts connected to energize said solenoid controlling retractable movement of said feeding means upon opening of the first mentioned contacts thereof, another switch on said press closed upon extreme upward travel of said cushion and head and controlling energization of the working cycle of said press, and a further switch on said supporting structure, closed by movement of said table and gripping means to an extreme advanced position, said further switch having its contacts connected in series with the contacts of said switch on the press for controlling the energization of the working cycle of the press, and preventing energization of the working cycle of the press until said gripping means has reached the extreme end of its feeding stroke.

3. In a control for a stock feeding apparatus adapted to feed stock to a press having an anvil and a cushion movable toward and from said anvil, said stock feeding apparatus having a table, means for translationally moving said table toward and from the press, gripping means on said table, means for moving said gripping means into gripping engagement with the stock, to feed the stock to said press upon translational movement of said table toward the press, and means operated by vertical movement of said cushion to control feeding movement of the stock thereto including a first solenoid controlling travel of said table away from the press, a second solenoid con-

trolling travel of said table toward the press, a third solenoid controlling engagement of said gripping means with the stock, a cam mounted on the cushion of the press and movable therewith upon vertical movement of said cushion, a first switch mounted on the press, said switch having two contacts one of which is closed and the other of which is open during movement of said table toward the press, a relay having a coil connected with the closed contact of said switch and energized upon closing of said contact, the open contact of said switch being connected with said first solenoid to energize said solenoid when closed, said relay having contacts connected with said third solenoid, to hold said solenoid closed, and said first switch having an operating lever connected and positioned to be engaged by said cam upon engagement of said cushion with said anvil, to move said switch to open said closed contact and break the circuit to said relay coil, causing opening thereof and release of said gripping means, and to close said open contact and close the circuit to said first solenoid, energizing said solenoid, to effect travel of said table away from the press, and a second switch spaced from said first switch on said press and having an operating lever connected thereto and positioned to be closed by engagement of said cam upon upward travel of said ram and cushion only, to close the circuit to said second solenoid, and energize said second solenoid and effect travel of said table toward the press, said first switch closing the circuit to the coil of said relay upon disengagement of said cam from its operating handle, to energize and close said relay upon upward travel of said cushion and disengagement of said cam from said first switch, and a third switch on the feeding apparatus closed by engagement with said table at the end of retractable travel thereof, to energize said third solenoid, to effect engagement of said gripping means with the stock prior to the feeding stroke of said table.

4. In a press having a vertically movable reciprocating cushion and head, a supporting structure, a stock feeding mechanism carried by said supporting structure and arranged to feed stock to the press and including a reciprocably movable table, gripping means on said table for clamping engaging the stock, means moving said table toward and from the press, means engaging said gripping means with the stock, valve means controlling the engagement of said gripping means with the stock, valve means controlling movement of said table toward the press, other valve means controlling return movement of said table, and individual solenoids connected with said valve means to operate the same, the improvements comprising a relay, a cam movable with the cushion and head of the press, two spaced switches on the press and operated by said cam in a predetermined sequence, one being associated with said relay and having a contact connected to energize the coil of said relay when closed and a second contact closing upon opening of said first contact, to energize said solenoid effecting movement of said feeding mechanism from the press, the other of said switches being associated with said solenoid controlling movement of said table toward the press and energizing the same upon the closing of said relay, and a switch on the supporting structure closed by movement of said table at the end of return travel thereof and having a contact in series with the coil of said relay and the first

contact on said one switch, said first contact of said one switch closing upon the engagement of said head with the stock, and said switch on said supporting structure closing at the end of return travel of said table and completing a circuit through the coil of said relay and the first contact of said one switch to close said relay and maintain said relay closed and also to energize said solenoid controlling operation of said gripping means through the contacts of said relay, to engage said gripping means and hold said gripping means in engagement with the stock during travel of said table toward the press.

5. In a press having a vertically movable reciprocating cushion and head, supporting structure, a stock feeding mechanism carried by said supporting structure and arranged to feed stock to the press and including a reciprocably movable table, gripping means on said table for clampingly engaging the stock, means moving said table toward and from the press and other means moving said gripping means into engagement with the stock, a first valve controlling engagement of said gripping means with the stock, a second valve controlling movement of said table toward the press, a third valve controlling return movement of said table, and individual solenoids connected with said valves to operate the same, the improvements comprising a relay, a cam movable with the cushion and head of the press, two spaced switches on the press and operated by said cam in a predetermined sequence, one of said switches being associated with said relay and having a first contact connected to energize the coil of said relay when closed and a second contact closing upon opening of said first contact to energize the solenoid operating said third valve and effect return movement of said table, the other of said switches having one contact energizing said solenoid operating said second valve controlling

movement of said table toward the press, a switch on the supporting structure closed by movement of said table at the end of return travel thereof and having a contact in series with the coil of said relay and the first contact on said one switch, said first contact of said one switch closing upon engagement of the cushion with the stock and completing a circuit through said switch on said supporting structure to energize the coil of said relay and maintain said relay closed and hold said gripping means in engagement with the stock during travel of said feeding means toward the press, a third switch on said press closed upon extreme upward travel of said head and controlling energization of the working cycle of the press, and a further switch on the supporting structure closed by said table at the end of its feeding stroke, said last mentioned switch having contacts in series with the contacts of said third switch on the press and preventing energization of the working cycle of the press until said table is at the end of its feeding stroke.
